US0D1015285S

(12) **United States Design Patent** (10) **Patent No.:** **US D1,015,285 S**
(45) **Date of Patent:** **** Feb. 20, 2024**

(54) **VIDEO STREAMING DEVICE**

(71) Applicant: **Verizon Patent and Licensing Inc.**,
Basking Ridge, NJ (US)

(72) Inventors: **Robert Stewart**, Point Pleasant, NJ (US); **Andrew Nicholas Toth**, Telford, PA (US); **Huiyu Wang**, Basking Ridge, NJ (US); **Christopher Emmons**, Stratford, NJ (US); **Carlos Javier Borlando**, Lansdale, PA (US); **Lance Koenders**, Mendham, NJ (US); **Caleb Jones**, Brooklyn, NY (US); **Aiden Lee**, Long Island City, NY (US); **Joe Frankl**, Brooklyn, NY (US); **Reid Schlegel**, Oradell, NJ (US); **Easson Lin**, Taoyuan (TW); **Mark Su**, Taoyuan (TW)

(73) Assignee: **Verizon Patent and Licensing Inc.**,
Basking Ridge, NJ (US)

(**) Term: **15 Years**

(21) Appl. No.: **29/788,586**

(22) Filed: **Jun. 29, 2021**

(51) **LOC (14) Cl.** 14-03
(52) **U.S. Cl.**
USPC **D14/125**

CLAIM

The ornamental design for a video streaming device, as shown and described.

DESCRIPTION

FIG. 1 is a front perspective view of our new design.

FIG. 2 is a bottom perspective view of the new design.

FIG. 3 is a front view of the new design.

FIG. 4 is a rear view of the new design.

FIG. 5 is a top view of the new design.

FIG. 6 is a bottom view of the new design.

FIG. 7 is a left-side view of the new design; and,

FIG. 8 is a right-side view of the new design.

The broken lines in the figures form no part of the claimed design. The characters shown in broken lines in FIGS. 5 and 6 form no part of the claimed design.

1 Claim, 8 Drawing Sheets
